WALL STRUCTURE FOR RAILWAY CARS

Garth G. Gilpin, Riverside, Ill., assignor, by
mesne assignments, to Standard Railway
Equipment Manufacturing Company, a cor-
poration of Delaware

Application April 2, 1937, Serial No. 134,592

8 Claims. (Cl. 105—410)

The invention relates to railway cars, and more particularly to end wall (or side walls) therefor which perform several functions, to wit: that of retaining the lading in the car; holding the car superstructure square; resisting the thrust of the shifting load, and protecting the lading from the weather.

The construction is also adaptable to a car roof which holds the car square and also holds the side walls in place. The structure is also adaptable to side doors for railway cars and side walls of open top gondola and hopper cars.

One of the primary objects of the invention is to associate two spaced apart relatively light weight metallic sheets with struts therebetween so that these elements will cooperate to form a very strong beamlike structure between the side walls of the car to enable the wall to perform the functions enumerated above.

Another object of the invention is to provide a structure wherein very light weight metallic sheets may be used which is made possible by the distribution of the metal in my arrangement of parts; such for instance, as sheet steel, aluminum or corten. Galvanized sheets could be used as the galvanization would not be cracked or broken in my arrangement. Furthermore, by the fact that the light weight sheets are not stretched or deformed in shaping them for use in my structure, such as when metallic sheets are formed into a plurality of corrugations.

Another object of the invention is to form such a double sheet wall (with struts therebetween) in which the inner sheet is flat and the outer sheet is outwardly bowed, whereby a smooth interior surface of the wall is provided which is desirable for package lading and for explosive lading, and whereby the relatively narrow marginal portions provide space for the ladders when the structure is used in an end wall for a railway car; provides tunnel clearance at the eaves of the car when the structure is used in a roof of a railway car, and provides clearance for the roller brackets or for hangers when the structure is used in a side door for a railway car.

Another object is to provide a structure in which the component elements may be welded or riveted together and wherein the wall may be assembled in the field and applied to the car as a unit.

Another object is to provide members at the margins of the metallic sheets which provide means to secure the two sheets together for beam action; provides increase shear value at the ends of the beams, and, if desirable, to pro-

vide means to attach the wall to other elements of the car structure.

In the drawings:

Fig. 1 shows an end of a railway car having my improved wall structure.

Fig. 2 is a section on line 2—2 of Fig. 1.

Fig. 3 is a section on line 3—3 of Fig. 1.

Fig. 4 is an enlarged section on line 4—4 of Fig. 1.

Fig. 5 is an enlarged section on line 5—5 of Fig. 1.

Fig. 6 is an enlarged section on line 6—6 of Fig. 1.

Fig. 7 is an enlarged section on line 7—7 of Fig. 1.

Fig. 8 shows one of the struts between the wall sheets.

Figs. 9 and 10 show a modified structure wherein the struts and frame members are separate members.

Fig. 11 shows another modified structure.

Figs. 12 and 13 show an arrangement of the struts wherein they are closer together adjacent the floor of the car than elsewhere.

The drawings show the usual parts of the car, such as side plate 2; side sill 3; end sill 4; striking casting 5 and flooring 6.

The wall comprises an inner flat metallic sheet 7, an outwardly bowed metallic sheet 8 with the opposite margins 9 thereof adjacent but preferably spaced from the adjacent margins 10 of the inner flat sheet 7 and a plurality of struts 12 are positioned between the sheets and formed and secured thereto so that the inner metallic sheet; the outer bowed metallic sheet and the struts cooperate to provide a beam wherein the outer metallic sheet 8 forms the tension member and the flat sheet 7 forms the compression member of the beam for a force from within the car and vice versa for a force from outside the car.

In the preferred form the inner metallic sheet 7 is provided with wings 15 and the outer bowed metallic sheet is provided with wings 16 which are preferably in spaced relation to the wings 15. Each strut 12 comprises a web 18, an inner flange 19 and an outer flange 20, which flanges are secured to the inner (7) and outer (8) metallic sheets, preferably by welding 22—23 (or one flange riveted and the other welded). The width of the web 18 varies to conform to the varying distance between the inner and outer metallic sheets and the flanges 19 and 20 vary correspondingly; that is, the flanges increase in width in proportion to the decrease in width of the web so that the neutral axis of the structure is sub-

stantially midway between the metallic sheets whereby the metal is distributed to obtain the maximum strength thereof as a beam. These flanges 19-20 merge together (as best shown in Fig. 8) and are bent to form wings 25 which are positioned between the wings 15 and 16 of the inner and outer metallic sheets. The struts 12 are preferably so formed and positioned that the edges 26 of adjacent struts are close together so that they may be secured together by welded material to form a substantially continuous reinforcing member between the wings 15 and 16 of the two metallic sheets. (See Fig. 1.) The wings and struts are secured to the side wall 28 by rivets 29 (or other means). The metallic sheets are preferably spaced apart adjacent the side walls of the car to provide greater shear value at the ends of the beam (along the line 30 in Fig. 7).

20 If more than one inner metallic sheet is used they may be welded together and to a flange, as at 31. If two outer metallic sheets are used they may be welded together and to a flange, as at 32, or may be riveted together. The struts may be riveted to the outer sheets and then the inner sheet may be welded to the struts, thus maintaining a smooth interior surface for the car wall.

In the modification shown in Figs. 9 and 10 a separate corner post 40 (or other frame member) 30 is shown, comprising an arm 41 for attachment to the car side wall 42 (or other car element) and another arm 43 having parts 44 normal to the other arm 41 and other parts 45 alternating with the parts 44 positioned at an acute angle 35 to the parts 44. Such an arm may be called corrugated. The inner metallic sheet 48 is secured to the parts 44 and the outer bowed metallic sheet 49 is secured to the parts 45. The outer metallic sheet 49 is continued and bent to form a flange 50 overlapping and secured to the frame member 40 by the rivets 51. The struts 53 extend between and are secured to the frame members 40, preferably by welded material 55.

Fig. 11 shows a modification wherein the outer sheet 60 overlaps the side wall 61 and the frame member 62 has one arm 13 secured to the side wall and flange 64 of the outer wall and another arm 65 overlapping and secured to the inner sheet 66 and strut 67.

50 My wall may be assembled and applied to the car as a unit.

Figs. 12 and 13 show how the struts 12 decrease in depth toward the sides of the car and how the flanges of the struts increase in width toward the side of the car. These Figs. 12 and 13 also show the struts nearer together adjacent the floor 6 of the car.

A wall, according to my invention, is relatively thick (normal to its general plane) adjacent its medial portion and relatively thin at its opposite margins, which is advantageous in an end wall for ladder (70) and grab iron clearances, and in a roof for tunnel clearances at the eaves of the car, and in a side door for a railway car for clearance for the roller brackets or hangers.

65 The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

70 1. A wall for a railway car comprising spaced apart frame members each comprising an arm for

attachment to car elements, and another arm having parts normal to the first mentioned arm and other parts alternating therewith positioned at an acute angle, a flat inner metallic sheet extending between and secured to the first mentioned part, an outwardly bowed outer metallic sheet extending between and secured to the last mentioned part, and a plurality of struts positioned between and secured to said sheets which extend between and are secured to said frame members.

2. A wall for a railway car comprising spaced apart frame members each comprising an arm for attachment to car elements, and another arm having parts normal to the first mentioned arm 15 and other parts alternating therewith positioned at an acute angle, a flat inner metallic sheet extending between and secured to the first mentioned part, an outwardly bowed outer metallic sheet extending between and secured to the last 20 mentioned part, and a plurality of struts positioned between and secured to said sheets which extend between and are secured to said frame members, said outer metallic sheet having flanges overlapping and secured to the first mentioned 25 arms of the frame members.

3. A wall for a railway car comprising spaced apart frame members each comprising an arm for attachment to car elements, and another arm having parts normal to the first mentioned arm 30 and other parts alternating therewith positioned at an acute angle, a flat inner metallic sheet extending between and secured to the first mentioned part, an outwardly bowed outer metallic sheet extending between and secured to the last 35 mentioned part, and a plurality of struts which extend between and are secured to said frame members, each of said struts having a web, an inner flange and an outer flange secured to the inner and outer metallic sheets respectively with 40 the web varying in width to conform to the distance between the metallic sheets and the flanges varying correspondingly in widths so that the neutral axis of the wall is midway between the metallic sheets.

4. An end wall for a railway car comprising spaced apart corner posts, each post comprising an arm for attachment of a car side wall, and a corrugated arm extending substantially normal thereto having alternating parts in angularly disposed planes, a flat inner metallic sheet extending between and secured to the inner of said alternating parts, an outwardly bowed outer metallic sheet extending between and secured to the outer of said alternating parts, and a plurality of horizontally disposed struts extending between and secured to said corner posts.

5. A wall for a railway car comprising a flat inner metallic sheet provided with wings at opposite margins thereof, an outwardly bowed outer metallic sheet with opposite margins thereof adjacent but spaced from the adjacent margins of the flat sheet, said bowed metallic sheet provided with wings at its said margins spaced apart from the wings of the flat sheet, and a plurality of struts positioned between said sheets, each of said struts having a web, an inner flange and an outer flange and secured to the inner and outer metallic sheets respectively with the web varying in width to conform to the distance between the metallic sheets and the flanges varying correspondingly in widths, said flanges merging together and bent to form wings which are positioned between the wings of the inner and outer metallic sheets.

6. A wall for a railway car comprising a flat inner metallic sheet provided with wings at opposite margins thereof, an outwardly bowed outer metallic sheet with opposite margins thereof adjacent but spaced from the adjacent margins of the flat sheet, said bowed metallic sheet provided with wings at its said margins spaced apart from the wings of the flat sheet, and a plurality of struts positioned between said sheets, each of said struts having a web, an inner flange and an outer flange and secured to the inner and outer metallic sheets respectively with the web varying in width to conform to the distance between the metallic sheets and the flanges varying correspondingly in widths, said flanges merging together and bent to form wings which are positioned between the wings of the inner and outer metallic sheets, the edges of the adjacent wings of the struts being welded together to form a waterproof structure.

7. A wall for a railway car comprising a flat inner metallic sheet, an outwardly bowed outer metallic sheet with opposite margins thereof adjacent but spaced from the adjacent margins of the flat sheet, members between said adjacent margins which fill the spaces therebetween to

provide a waterproof structure, said members being secured to said inner and outer sheets, a plurality of struts positioned between and secured to said sheets, which struts extend between and are secured to said members, and means to secure said members to elements of the car structure whereby said sheets, said struts and said members cooperate to form a beam between said car elements.

8. A wall for a railway car comprising a flat inner metallic sheet, an outwardly bowed outer metallic sheet with opposite margins thereof adjacent but spaced from the adjacent margins of the flat sheet, members having flat portions between said adjacent margins which fill the spaces therebetween and corrugated portions having alternating parts secured to said inner and outer sheets, a plurality of struts positioned between and secured to said sheets, which struts extend between and are secured to said members, and means to secure said members to elements of the car structure whereby said sheets, said struts and said members cooperate to form a beam between said car elements.
